UNITED STATES PATENT OFFICE.

OTIS A. MYGATT, OF NEW YORK, N. Y.

DESIGN FOR A SHADE, REFLECTOR, OR SIMILAR ARTICLE.

No. 40,181.

Specification for Design.

Patented July 27, 1909.

Application filed June 5, 1908. Serial No. 437,016. Term of patent 14 years.

To all whom it may concern:

Be it known that I, OTIS A. MYGATT, a citizen of the United States, residing at New York, in the county of New York and State of New York, have invented a new, original, and ornamental Design for Shades, Reflectors, or Similar Articles, of which the following is a specification, reference being had to the accompanying drawing, forming a part thereof.

Figure 1 is a top plan view of a shade embodying the invention. Fig. 2 is a bottom plan view of the same.

My design consists of a shade having on one side substantially radial ribs or prisms and on the other side ribs or prisms arranged in waved lines generally radial in direction, as shown. When viewed from either side

the ribs nearest to the eye are more clearly seen and those on the opposite side are more dimly seen through the glass body of the shade.

The optical results obtained from this design are peculiarly ornamental and novel and cannot be shown in a drawing. The appearance of the shade varies continually as the point of view changes, producing continually differing light effects.

I claim—

The ornamental design for a shade or reflector, or similar article substantially as shown and described.

OTIS A. MYGATT.
